UNITED STATES PATENT OFFICE.

HENRY C. HART, OF DETROIT, MICHIGAN.

CARPET-SWEEPER.

SPECIFICATION forming part of Letters Patent No. 240,701, dated April 26, 1881.

Application filed January 31, 1881. (No model.)

To all whom it may concern:

Be it known that I, HENRY C. HART, of Detroit, in the county of Wayne and State of Michigan, have invented an Improvement in 5 Carpet-Sweepers, of which the following is a specification.

My invention relates to new and useful improvements in carpet-sweepers, by means of which economy in construction is combined 10 with the requisite strength and durability. Hence my invention consists in the peculiar details of construction of the various parts, their various combinations and operation, as more fully hereinafter described.

15 Figure 1 is a perspective view, looking at the bottom, with a portion of one of the end walls removed, and with a locking-plate removed and reversed. Fig. 2 is a cross-section on the line 2 2 in Fig. 1. Fig. 3 is a like view 20 on the line 3 3 in Fig. 1. Fig. 4 is a like view on the line 4 4 in Fig. 1. Fig. 5 is a central vertical longitudinal section. Fig. 6 is a detached perspective view of the handle attachment. Fig. 7 is a bottom perspective view of 25 the dust-pan.

In the accompanying drawings, which form a part of this specification, A represents a shell made of steamed and bent wood, forming the top and sides, and B B' are the ends, also made 30 of wood and secured within the ends of the shell. This latter is made as described, in order to be sufficiently strong to allow the handle attachments to be secured thereto, instead, as where the shell is made of tin or thin sheet 35 metal, of being compelled to secure the handle to the ends of the device by means of a bail.

C C are a pair of wheels secured to short shafts properly journaled in the end B' and between it and the metal partition D.

40 A pulley, E, is secured to a shaft which is journaled in a standard, F. This standard is secured to the inner face of the end B', so as to have a vertical adjustability by means of the set-screw a, which passes through the 45 shell. The inner end of this pulley projects through the slot b, and its projecting end c is polygonal in form to engage with a similarly-shaped socket in the head d, which is secured on the end of the brush-shaft G.

50 A band or belt, H, passes over and under the wheels C and over the pulley E, and as

these wheels are the traction-wheels of the 55 sweeper, their rotation, by means of the belt, gives the necessary rotation to the brush-shaft.

The head d is made of malleable metal, and is provided with two or more ears, e, which embrace the sides of the wooden shaft G, and the head is secured in place by turning the ends of such ears into the sides of the shaft, 60 as shown in Fig. 5. The opposite end of this shaft G is provided with a pintle or journal, h, which rests in a suitable hole or indentation in the bell-crank-shaped support I. This support is supported through the top A by means 65 of the set-screw i, by means of which, also, the support is vertically adjustable. The long arm of the support is forced to incline inwardly by means of a spring, k.

When it is desired, for any purpose, to remove the brush, the long arm of the support is forced against the end B, and this engages the journal h, which allows the shaft to be drawn toward the end B, and this disengages the head d from the end of the shaft which 75 carries the pulley E.

J J are two dust-receiving pans, one on each side of the brush, and they are, alike in construction and operation. A description of one of them will be sufficient for the purposes of 80 this specification. The free or front edge of the pan is made with two inclined or beveled sides, a' a'', the latter of which facilitates depositing the dirt in the pan by the brush, while the former facilitates the dirt leaving the pan 85 when it is dumped. The pan is provided at each end with a journal or pintle, m m', the former engaging with the hole n n in the plate D, while the latter engages with a recess, o o, in the head B. The pintle m' is also provided 90 with a coil-spring, r, one end of which rests against the end of the dust-pan, while the other end rests against the inner face of the head B, so that the expansive action of the spring will, when the pan is in use and in place, force it 95 against the partition D, when the stud s, projecting from the face of said partition below the bottom of the pan, will sustain it in place.

K is a plate secured to the bottom of the end B. This plate is cast with a foot, t, designed to project below the end B the same distance that the wheels C project below the

end B' . The plate is also provided with a projecting lug, u , which enters the recess o and forms a bearing for the pintle m' . The plate is also provided with a side projecting hook, v , which sustains the lug w on the pan. When it is desired to dump or empty the pan it is drawn toward the head B , compressing the spring r until released from the stud s , and the lug w likewise released from the hook v , when the pan will partially rotate on its pintles, as shown in Fig. 2, the lug w passing between the hook v and the body of the plate to which it is attached.

A clip, L , is employed to secure the handle M to the case A . This clip is secured in place by suitable screws, as shown in Fig. 2, midway between the ends of the sweeper. The clip is provided with sockets x to receive the ends of the bail N , to which the handle is removably secured. The clip is provided with a curved tongue, y , springing from one side, and with a rigid stud, z , springing from the opposite side. When the sweeper is in use the position of the handle is shown in Fig. 2. When not in use the handle may be raised to a vertical position, as shown in dotted lines in the same figure, when the tongue y will hold the bail in contact with the stud z . A slight pull will cause the tongue to spring sufficiently to allow the bail to pass over it to regain the first position.

What I claim as my invention is—

1. In a carpet-sweeper, the pulley E , having a recess to receive the standard F , and provided with a shaft having a polygonal-shaped end, in combination with the division-plate D , having a slot, b , smaller than the diameter of the pulley, to allow a vertical movement of the pulley and yet hold it securely in place when the brush-shaft is removed, substantially as described.

2. In a carpet-sweeper, the combination, with a revolving brush-shaft, G , of the angular lever I , pressed downward and toward the brush-shaft by the spring k , and the set-screw i , for adjustably sustaining one end of said brush-shaft, substantially as set forth, whereby the spring serves to press the lever both downward and inward.

3. In a carpet-sweeper, the combination, with the pulley E , having a shaft with a polygonal-shaped end, and a recess to receive the standard F , of the standard F , the brush-shaft G , having at one end a socket, d , to fit the polygonal end of the pulley-shaft, and at the other end a journal, h , fitting in a recess

in the spring-lever I , and the spring-lever I , substantially as and for the purpose specified.

4. In a carpet-sweeper, the pulley E , having a polygonal-shaped end projecting through the partition-plate D , in combination with the brush-shaft and its head d , having a polygonal socket, the lever I , spring k , and set-screw i , for adjustably and removably securing the brush in place, substantially as described. 65

5. In a carpet-sweeper, the dust-pan J and the stop s on the partition D , in combination with the spring r for pressing the pan against said stop, substantially as and for the purpose specified. 70

6. In a carpet-sweeper, the plate K , constructed substantially as described, in combination with the head B and the pan J , substantially as and for the purpose set forth.

7. The plate K , having the foot t , lug u , and hook v , in combination with the head B and pintle m' of the pan J , substantially as set forth. 75

8. In a carpet-sweeper, the pan J , having pintles m m' and a lug, w , in combination with the head B , spring r , and the hook v on the plate K , substantially as described. 80

9. In a carpet-sweeper, the pan J , provided with pintles m m' and lug w , in combination with plate D and its stop s , head B , with its recess o , spring r , and plate K , substantially as and for the purposes specified. 85

10. In a carpet-sweeper, a handle secured to the top case thereof, centrally between the ends, and adapted to have a radial movement, 90 in combination with the fixed tongue Z and the spring-tongue y of the clip L , for securing it in a vertical position, substantially as and for the purposes described.

11. In a carpet-sweeper, and as a means of securing the handle thereto at a point midway between the ends thereof, the clip L , constructed substantially as described, in combination with the spring-tongue y and the bale N , as set forth. 95

12. In a carpet-sweeper, and as a means of securing and supporting the handle, the clip L , having recesses to receive the ends of the bail, and provided with a fixed tongue, Z , and a spring-tongue, y , in combination with the bail N , substantially as described, and for the purpose specified. 105
